The ornamental design for a gauge tape with horizontal markings as shown and described.

DESCRIPTION

FIG. 1 is an isometric view of a gauge tape with horizontal markings in accordance with the present application.

FIG. 2 is a front view of the gauge tape with horizontal markings.

FIG. 3 is a back view of the gauge tape with horizontal markings; and,

FIG. 4 is an end view gauge tape with horizontal markings. The gauge tape with horizontal markings is shown with a symbolic break in its length. The appearance of any portion of the article between the break lines forms no part of the claimed design.
